UNITED STATES PATENT OFFICE

2,438,193

SHOE ANTISKID DEVICE

Wayne Smith, Decatur, Ga.

Application November 8, 1946, Serial No. 708,609

2 Claims. (Cl. 36—7.7)

1

This invention relates to new and improved anti-skid means for application to shoes, boots and the like.

The primary object of this invention resides in the provision of means adapted to be quickly and easily secured on a boot, shoe or the like to prevent the slipping and sliding thereof when engaged in such activities as golf, baseball, mountain climbing and other such activities requiring a sure footing at all times.

Another object of this invention resides in the provision of an anti-skid device of the character described which is simple in its operation of detachable clamping means on a boot or shoe.

Still another object of this invention is the provision of an anti-skid device of the character described which is of extremely, simple, durable, and inexpensive design.

Still further improvements and advantages of this invention will readily appear to those skilled in the art when the following description is read in the light of the accompanying drawings in which:

Fig. 1 is a top plan view of the anti-skid device.

Fig. 2 is a bottom view of the device affixed to a shoe.

Fig. 3 is a vertical section of the device taken on line 3—3.

Fig. 4 is a side elevation of the device affixed to a shoe.

Referring now to the accompanying drawings, a flat, substantially rectangular metallic plate A has a curved end 1 on one short side thereof and two perpendicular flanged ears 2 and 3 extending upwardly from its two opposite long sides adjacent the curved end of the plate. The two ends of a conventional divided buckle strap 4 are secured by rivets 5, or the like, to the two ears 2 and 3 respectively to form an adjustable loop over the top of the metal plate A.

A plurality of metal spikes 6 are secured to plate A by conventional flanged heads 7 and 8, positioned on opposite sides of said plate with the sharpened ends of the spikes depending downward from the underside of the plate. These spikes, 6, are disposed and secured in definite design upon the area of the underside of the plate A so as to form a good surface engaging means on the plate.

Situated substantially in the center of the upper face of the plate A is a hard rubber triangular pad B, which is secured with one apex thereof disposed forward toward the curved end 1 of the plate A.

A conventional butt hinge 9 is secured to the

upper face, at the back end of the plate A with its axis 10 beyond and extending substantially parallel with the back end of said plate A, the extended half 11 of said hinge being pivotally mounted for movement about said axis.

A pair of elongated braces 12 and 13, of identically opposite construction, are secured by respective rivets 14, in spaced relationship, to the extended half 11 of the hinge 9, perpendicular to the hinge axis. These braces 12 and 13 are provided with perpendicular upwardly disposed flanged ears 15, on their outside edges, which are adapted by hooked ends 16 thereon to securely clamp the extended portion 17 of a shoe sole 18.

These braces 12 and 13, are also provided with perpendicular depending flanged ears 19 on their inner adjacent edges. These ears 19 are provided with apertures which loosely receive a threaded bolt 20 therethrough by means of which the extended ends of the braces are adjusted to varied width shoes. Bolt 20 may have continuous threads and a nut screw threaded thereon to compress the lever ears 19, or if desired, may be provided as a conventional skate clamp screw having oppositely threaded end portions engaged in oppositely screw threaded apertures, the ears 19, in such case, preferably being pivotally secured to the respective braces.

By placing the forward portion of the shoe sole 30 on the upper surface of the rubber pad B, which forms a non-slide engagement with the sole, the strap 4 may be looped upwardly and tightly over the top portion of the shoe thus securing the plate A in a tight adjacent position thereagainst.

The braces are then pivoted on their hinge axis upwardly so that the hooked ends 16 of the ears 15 may be caused to engage the extended portion 17 of the sole 18. By turning the bolt 20 the hooked ends 16 are drawn together clamping the braces upon the arch portion of the shoe sole 18.

Thus it may be seen that a durable, simple and inexpensive non-skid device has been provided which may be quickly and easily attached to and removed from a shoe, boot or the like.

Having thus described and explained the construction and use of this device, what I desire to claim and secure by Letters Patent is:

1. A non-skid shoe attachment of the character described comprising, a flat metallic plate of substantially rectangular shape, a plurality of surface engaging spikes secured to and depending from said plate in a set pattern, a pair of oppositely disposed vertical ears upwardly flanged from forward sides of said plate, an adjustable strap secured to and interconnecting said ears in

a manner adapting it to encircle the shoe upper and maintain said plate adjacent the underside of the sole of said shoe, a pair of oppositely identical braces disposed at the rearward end of said plate, hinge means and pivot means attaching said braces to said plate for movement about a common axis substantially parallel to the rearward edge of said plate and about individual axes substantially perpendicular to said common axis, means carried by the outside edges of said braces adapted to securely engage the extended portion of the sole of said shoe, and screw means operatively connecting said braces to clamp said shoe sole between said sole-engaging means.

2. A non-skid shoe attachment of the character described comprising, a flat metallic plate of substantially rectangular shape adapted to partially conform with a forward sole portion of a shoe, a plurality of surface engaging spikes secured to and depending from said plate in a predetermined and desired pattern, a triangular hard rubber pad secured to the upper face of said plate substantially in the center thereof adapted for non-slip engagement with the sole of said shoe, a pair of vertical ears upwardly flanged from the opposite forward sides of said plate adapted to extend

upwardly past the extended sole portion of said shoe, an adjustable buckle strap secured to and interconnecting said ears in a manner adapting it to encircle the shoe upper and maintain said plate and said pad adjacent the underside of the sole of said shoe, a pair of oppositely identical braces hinged longitudinally with and on the rearward end of said plate, vertically disposed ears carried by the outside edges of said braces adapted at their ends to securely engage the extended portion of the sole of a shoe in substantially the arch section thereof, and threaded means interconnecting said braces for adjusting the spaced relationship between the securing edges thereon.

WAYNE SMITH.
